UNITED STATES PATENT OFFICE.

ISAAC HELLERMAN, OF NEW YORK, N. Y.

BOOKMARK.

Application filed July 27, 1922. Serial No. 577,800.

To all whom it may concern:

Be it known that ISAAC HELLERMAN, citizen of the United States, residing at the city of New York, in the county of Kings and State of New York, has invented certain new and useful Improvements in Bookmarks, of which the following is a specification.

This invention relates to book marks. 10 One object thereof is to provide a device of the character described which shall be readily attached to a book and mark a desired page thereof.

Another object of this invention is to provide a device of the character described which may be readily detached from the book.

A still further object of this invention is to provide a device of the character described which shall extend flush with the top of the book, shall be neat in appearance, simple in construction, and comparatively cheap to manufacture.

Other objects of this invention will in 25 part be obvious and in part hereinafter pointed out.

This invention accordingly consists in the features of construction, combinations of elements and arrangement of parts which 30 will be exemplified in the construction hereinafter described and of which the scope of application will be indicated in the following claims.

In the accompanying drawings, in which 35 is shown one of various possible illustrative embodiments of this invention,

Fig. 1 is a perspective view showing an embodiment of my invention attached to the front cover of a book;

Fig. 2 is a plan view of the embodiment 40 of my invention shown in Fig. 1; and

Fig. 3 is a side elevation thereof.

Referring in detail to the drawing, 10 is a book, having the front and rear covers 45 11, 11' respectively and the leaves 12 included therebetween. The book mark 13 comprises a clamp member 14 formed preferably of resilient material such as worked copper or silver, and having the spaced inner and outer clamping plates 14^a, 14^b respectively. The latter are preferably stamped from one flat piece of material of any desired design or shape and then bent over so as to provide the clamp 14 adapted 50 to engage in the space 14^c either the front or rear book cover, or to embrace a number of

leaves of the book. I prefer to make the rear clamping plate 14^b substantially longer than the front plate 14^a so as to afford a firmer hold on the book. Furthermore, 60 the plates 14^a, 14^b are inclined toward each other so that the clamp is automatically adjusted to various thicknesses of book covers. For marking the place in the book, the usual 65 ribbon 15 or strip of other thin flexible material is provided. The latter is suspended from a wire member 16 disposed in the eye portions 17 preferably formed integral with the clamp. The eye portions 17 are disposed adjacent each upper end 18 of the 70 rear clamp plate 14^b and the wire member 16 extends adjacent the upper edge thereof. The eye portions 17 may readily be formed after the stamping has been bent to provide 75 the clamp by passing the latter through a suitable hand die. The wire 16 is then inserted and riveted at either end if so desired, and the ribbon then suspended therefrom.

The application of the device is now clear. 80 The book mark is clamped to the book cover in the manner shown in Fig. 1, or to a plurality of leaves, so that the ribbon marker extends downwardly flat on the inner face of the cover or of one of the leaves. When 85 it is desired to mark a particular place in the book, the ribbon is raised and stretched over the upper edges of the leaves and then stretched across the desired page. While 90 reading, the ribbon may be allowed to hang loosely away from the book and inserted at the page to be marked when desired.

It is clear that there is thus provided a neat and simple device for marking the page of a book which may be attached 95 thereto without harming the book, or without detracting from the appearance of the book or interfering with the comfort of the reader. Furthermore, by attaching the book mark to a plurality of the book pages, 100 the book may be replaced on the shelf as if no book mark were attached thereto.

It will thus be seen that there is provided a device in which the several objects of this invention are achieved and which is well 105 adapted to meet the conditions of practical use.

As various possible embodiments might be made of the above invention and as various changes might be made in the embodiment above set forth, it is to be understood that all matter herein set forth or

shown in the accompanying drawings is to be interpreted as illustrative and not in a limiting sense.

Having thus described my invention 5 I claim as new and desire to secure by Letters Patent:—

A book marker comprising a one-piece clamp having gripping jaws of unequal length adapted to engage with the cover of 10 a book, a pair of eye members formed integrally with said clamp to extend at right

angles to the longer of said jaws, a rod member disposed between and secured by said eye members, and a marker extending along said rod member, said marker being adapted to swing in a plane at right angles to the cover that normally engages with said clamp. 15

In testimony whereof I affix my signature.

ISAAC HELLERMAN.
